(57) CLAIM

The ornamental design for a pair of socks with neo-pagan style symbols, as shown and described.

DESCRIPTION

The FIGURE is a bottom side perspective view of a pair of socks with neo-pagan style symbols showing my new design.

The broken lines in the drawings depict environmental structure and form no part of the claimed design. The environmental structure is shown with a symbolic break in its length. The appearance of any portion beyond the break line forms no part of the claimed design.
